United States Patent Office

Des. 208,784

Patented Oct. 3, 1967

208,784

HEARING AID

William M. Sanzone, Minneapolis, Minn., assignor to The
Telex Corporation, Tulsa, Okla., a corporation of
Delaware

Filed Dec. 19, 1966, Ser. No. 5,107

Term of patent 14 years

(Cl. D26—14)

FIG. 1

FIG. 2

FIG. 3

FIG. 4

FIG. 5

FIG. 6

FIG. 7

FIG. 8

FIG. 9

FIG. 1 is a perspective view, to a reduced scale, of a hearing aid, showing my new design;

FIG. 2 is a left side, top and front perspective view;

FIG. 3 is a right side, top and front perspective view, to the same scale as FIG. 2;

FIG. 4 is a top plan view, to a reduced scale;

FIG. 5 is a left side elevational view, to the same scale as FIG. 4;

FIG. 6 is a front elevational view, to the same scale as FIG. 4;

FIG. 7 is a right side elevational view, to the same scale as FIG. 4;

FIG. 8 is a rear elevational view to the same scale as FIG. 4; and

FIG. 9 is a bottom plan view, to the same scale as FIG. 4.

The broken line showing of a wearer's ear in FIG. 1 is for illustrative purposes only.

I claim:

The ornamental design for a hearing aid, as shown and described.
